UNITED STATES PATENT OFFICE.

EDWARD F. CREEVY, OF CHICAGO, ILLINOIS.

TROLLEY FOR ELECTRIC RAILWAYS.

No. 821,611.

Specification of Letters Patent.

Patented May 29, 1906.

Application filed July 11, 1900. Serial No. 23,190.

To all whom it may concern:

Be it known that I, EDWARD F. CREEVY, a citizen of the United States; residing at Chicago, in the county of Cook and State of Illinois, have invented certain new and useful Improvements in Trolleys for Electric Railways, of which the following is a full, clear, and exact description, reference being had to the accompanying drawings, and to the letters 10 of reference marked thereon, which form a part of this specification.

This invention relates to trolleys for electric railways, and more particularly to that class of electric railways in which the electric current is conveyed through conduits located beneath the track. Heretofore in railways of this class it has usually been necessary to provide a conduit beneath the center of each track, thereby necessitating a separate and 20 distinct excavation for each track. Obviously if the track is already laid this necessitates interruption of traffic and non-use of the road or part of the same for considerable intervals of time.

25 My invention contemplates a conduit located at the side of the track and in the case of parallel tracks located between said tracks and of such a nature that the same may be constructed without interruption of traffic or 30 serious inconvenience and into which the trolley projects from the side of the car.

The invention consists in the matters hereinafter described, and more fully pointed out and defined in the appended claims.

35 In the drawings, Figure 1 is a cross-sectional view of two parallel tracks having conduits provided with trolleys embodying my invention. Fig. 2 is a longitudinal section of the same on line 2-2 of Fig. 1. Fig. 3 is a 40 front elevation, partly broken, of the trolley. Fig. 4 is a section on line 11-11 of Fig. 3. Fig. 5 is a view similar to Fig. 3, but showing the trolley-shaft in longitudinal section and illustrating the wiring. Fig. 6 is a side elevation 45 of the trolley-carrier. Fig. 7 is a rear end elevation of the same. Figs. 8 and 9 are respectively details of pivotal devices for the trolley-arm.

In said drawings, in which the invention is 50 shown as applied in a double track, the rails of which are indicated by L L, respectively, A indicates a frame or casting adapted to be set in the roadway between said tracks. As shown, the same is symmetrical and forms 55 the frame for a double conduit, one for each of said tracks and located on the adjacent

sides of the same. Said frames are provided above each conduit-opening with upwardly-extending parts a' a', forming between the same a slot to receive a trolley-arm. The 60 top of said frame, as shown, is approximately straight and is provided at the ends with projections a, adapted to form supports for the adjacent or inside rails of each track, as shown in Fig. 1. The base of said casting-frame is 65 relatively broad to afford adequate support for the track-bed and street above the same. B indicates a trolley-arm attached to a car, extending downwardly through said slot into said conduit. The lower end of the same, as 70 shown, is provided with a contact device consisting of a shaft B', provided on each end with a trolley-wheel b b, adapted to run on electrical conducting wires or rails secured on each side of the conduit on arms extending therefrom and herein indicated as a''. Said frames A are bedded in the road-bed, as shown in Fig. 1, the inner adjacent rails of the track resting on each end of the same and are surrounded by concrete or other desired 75 material, &c., which between said frames forms the walls of the conduit. A' A' indicate conductor-wires, of which two are shown in each conduit, located one on each side of the conduit at the same level and equally 80 distant from the trolley-slot. Said wires may be of any desired form or may be rails, if preferred, and are secured in the arms a'' a'', as shown, by means of insulated clamps of metal or other desired material. Said clamps, 85 as shown, each comprise interfitting flanged sleeves a⁴ and a⁵ of indurated fiber, glass, or other insulating material, through which passes one member a³ of the clamp, which is provided on its lower end with a nut adapted 90 to firmly hold the same in place. a⁶ indicates the opposite member of the clamp, similar in shape to the upper of the clamping member a³ and adapted to be secured thereto by means of a transverse bolt. On the adjacent faces of the upwardly-extending parts a' a' on said frames on each side of the trolley-slot are secured, as shown, plates a⁸, preferably of metal, and secured thereto by bolts or like means and extending between the 95 frames, as indicated in Fig. 2. Said plates are adapted to afford a smooth vertical wall for said slot between the frames. Said frames may be placed any desired distance apart and obviously, if preferred, may be 100 made single instead of double to be used for a single track.

In a construction of this class it is desirable that the trolley or contact device used therewith possesses a maximum of flexibility to adapt itself to the motion of the car, which 5 not only has lateral swing or sway, but also a vertical oscillation due in part to inequalities in the track. Said trolley or contact device is constructed as follows: The transverse axle B', constructed of wood or other insulating material, is provided at its ends with grooved trucks or contact-wheels b. As shown in Figs. 3, 4, and 5, said wheels b are secured in said axle B' by means of fittings or caps b', adapted to clamp onto the end of said 10 axle and provided with an axial bearing adapted to receive the stub-axle b² of metal. A bolt passes transversely through said fitting and said stub-axle, as indicated in Figs. 3, 4, and 5, and rigidly holds the same from 15 rotation. Obviously said fittings b' may be at any time tightened upon the axle by means of said bolt. The trolley-wheels b b are rotatively journaled upon said stub-axles and are secured thereon by means of a cotter-pin 20 or the like. Said shaft B' is pivoted in the trolley-arm B as follows: Said trolley-arm is provided at its lower end with an enlarged head B², transversely apertured to receive the shaft B' and consisting of a fitting b³, rigidly bolted on each side of the lower extremities of the same and provided therein with horizontal bearing-sockets adapted to receive the trunnions b⁴ b⁴ of a ring B⁵, which is rigidly secured centrally on said shaft, as is 25 shown in dotted lines on Fig. 3. Said shaft is then inserted in the aperture in the head of the trolley-arm, which is elliptical in cross-section, or, in other words, of greater diameter vertically than horizontally. The fittings 30 b³, bolted to the trolley-arm, hold said axle in position, while permitting the axle ends to have considerable amplitude of movement vertically. Said trolley-arm B extends upwardly and forwardly, as shown, in a compound curve, and the same at its lower end in 35 said slot is relatively broad longitudinally of the slot and thin transversely thereof to afford the requisite strength and yet not require said slot to be objectionably wide. At 40 its upper end it passes through the rearwardly-directed end of a yoke B⁴. The inner end of said trolley-arm passes inwardly between the arms b⁵ b⁵ of said yoke and passes centrally through a collar B⁶, provided at its 45 upper and its lower side with a conical socket adapted each to receive the complementary head of the studs B⁷ B⁷, which pass through the arms of the yoke on each side of said collar and are at all times held extended in engagement therewith by means of the springs 50 b⁸ b⁸, which are secured on said studs and engage with one end the head thereof and with the other end the inner side of the yoke-arms, respectively. The trolley-arm is journaled 55 in the head of said yoke by means of a shaft

B⁵, which passes transversely through the same and is provided with bearings in the yoke-head on each side of the same. A cap b⁷, forming the upper part of the bearing, is adapted to fit over said shaft or trunnions 70 and is rigidly secured in place by means of bolts or the like. B⁸ indicates a laterally-directed arm rigidly secured to the yoke B⁴ and adapted at its inner end for engagement with one of the truck-frame members of a car, (indicated by F.) Said trolley-arm being pivoted on the shaft B⁵ necessarily permits considerable vertical oscillation of the car without affecting the trolley, inasmuch as the springs b⁸ b⁸ are adapted to sustain a portion 75 of the weight of the trolley and yield sufficiently to permit the desired freedom of motion. The electrical connection from said trolley-wheel b is made by means of a wire b⁹, which leads from the end of the stud-shaft b² 80 through the shaft B' to said trolley-arm and is led upwardly therefrom on the rear side of the same to a motor secured on the car and of any desired form.

The operation of my device is as follows: 90 The trolley-wheels passing along the conductor rails or wires transmit the current through the trolley to the motor and the axle on which they are journaled being hung so as to allow considerable vertical movement of its ends, 95 the wheels will at all times rest upon their respective rails and the danger of cutting off motive circuit be thereby obviated, while differences between the planes of the trolley-rails and the track are provided for by having the trolley-arm pivoted in the yoke.

Obviously a trolley constructed in this manner will be adapted to adjust itself to inequalities in the track and trolley-rails and can be easily and cheaply installed after the 105 road-bed and track have been laid without seriously interfering with the same.

I claim as my invention—

1. In a device of the class described, a trolley-arm adapted to be pivotally supported upon a car or the like and to depend therefrom into a conduit the lower end of said arm being provided with a centrally-apertured head said aperture in said head having greater diameter vertically than horizontally, an axle 110 pivoted in said aperture transversely of the trolley-arm and adapted to oscillate vertically and means for holding said axle in rigid alinement longitudinally of said trolley-arm.

2. In a device of the class described, a trolley-axle comprising a central shaft of non-conducting material provided centrally with a circumferential band or ring provided on opposite sides with trunnions, means at each end of said axle for securing thereon a 115 trolley a trolley-wheel and electrical connections communicating with the same.

3. In a device of the class described, a trolley-axle comprising a central shaft of non-conducting material provided centrally with 120

a circumferential band or ring provided on opposite sides with trunnions, whereby the axle is pivoted to a trolley-arm, stub-shafts secured at each end of said axle, trolley-
5 wheels thereon and conductors leading inwardly from said stub-shafts and adapted to be connected with a motor.

4. The combination with a trolley-arm pivoted laterally on a car and adapted to oscillate vertically and laterally and extending at its lower end within a conduit located below and at one side of the track, an apertured head at the lower end of said trolley-arm and means for securing an axle therein
10 15 acting to permit vertical oscillation of the ends thereof.

5. The combination with a trolley-arm adapted to be pivoted laterally on a car and to extend downwardly within a conduit below the same, of an axle pivoted at the lower end of said trolley-arm, a trolley-wheel at each end of said axle adapted for contact in said conduit with a conductor and conductor-wires having contact with said trolley-
20 25 wheels and leading therefrom to a motor supported on the car.

6. In a device of the class described a trolley-arm adapted to depend within a conduit, means adapted to permit vertical oscillation only of said arm, comprising a yoke secured on a car-frame provided at its end with a bearing adapted to receive lateral trunnions on said trolley-arm, the upper end of said trolley-arm being directed forwardly and
30 35 adapted to be engaged between oppositely-acting springs secured between the yoke-arms.

7. In a device of the class described, a rearwardly and downwardly directed trolley-arm provided at its lower end with a head adapted to afford engagement for a vertically-oscillating axle provided at its ends with contact devices, means for permitting said trolley-arm to oscillate vertically comprising a bearing supported from a car or the like and beyond which the upper end of said trolley-arm extends, and springs engaging said end of said trolley-arm and acting to hold the same in operative position.

50 8. The combination with a vertically-oscillating trolley-arm adapted to depend within a conduit and provided at its lower end with a laterally-apertured head, an axle of non-conducting material pivoted in the aperture in said head and provided at its ends with clamps adapted to engage metallic stub-axes, a trolley-wheel on each stub-axle and

a conductor located within the axle leading from each stub-axle upwardly along the trolley-arm and adapted to afford electrical connection with an electric motor.

9. The combination with a rearwardly and downwardly directed trolley-arm adapted to be pivoted on a car-frame and adapted to oscillate vertically while rigidly secured from lateral oscillation, and provided at its lower end with a head having a lateral aperture extending therethrough, an axle of non-conducting material provided centrally with laterally-directed trunnions having a bearing in forwardly and rearwardly directed sockets in said head opening into said aperture, contact devices secured on each end of said axle and conductors connected with said contact devices and leading through said axle and upwardly along said trolley-arm.

10. The combination with a downwardly and rearwardly directed trolley-arm having an apertured head on the lower end thereof of a shaft pivoted at its center in said head and adapted for vertical oscillation, an adjustable cap on each end of said head, an axle rigidly engaged therein, a wheel journaled on each axle and an electrical conductor connecting said axles.

11. In a device of the class described the combination with a trolley-arm of a transversely-apertured head thereon, a shaft adapted to extend through said head, a ring rigidly engaged centrally on said shaft and provided with trunnions adapted to engage in sockets in said head, a trolley-wheel journaled at each end of said shaft, a conductor-wire extending through the shaft and connecting said wheel with the trolley-arm and means permitting vertical oscillation of said trolley-arm.

12. In a device of the class described the combination with a trolley-arm of a transverse shaft pivoted centrally at one end thereof, means on each end of said shaft adapted to engage electrical conductors, a yoke affording a pivotal support for said arm and springs in said yoke adapted to normally hold said arm centrally thereof.

In testimony whereof I have hereunto signed my name in the presence of two subscribing witnesses.

EDWARD F. CREEVY.
